UNITED STATES PATENT OFFICE

161,717

X-RAY TABLE

Robert J. Stava, University Heights, and William F. Schneerer, Cleveland Heights, Ohio, assignors to Picker X-Ray Corporation, Waite Manufacturing Division, Inc., Cleveland, Ohio, a corporation of Ohio

Application January 17, 1950, Serial No. 7,294

Term of patent 14 years

(Cl. D61—1)

To all whom it may concern:

Be it known that we, Robert J. Stava and William F. Schneerer, citizens of the United States, of University Heights, county of Cuyahoga and State of Ohio, and of Cleveland Heights, county of Cuyahoga and State of Ohio, respectively, have invented a new, original, and ornamental Design for X-Ray Table, of which the following is a specification, reference being had to the accompanying drawings, forming a part hereof.

Fig. 1 is a perspective view of the X-ray table embodying the new design, the view being taken from the front of the table; and Fig. 2 is a perspective view showing the rear of the table.

We claim:

The ornamental design for an X-ray table, as shown.

ROBERT J. STAVA.
WILLIAM F. SCHNEERER.
